UNITED STATES PATENT OFFICE.

JOHN S. ADAMS, OF ELGIN, ILLINOIS, ASSIGNOR TO THE DETROIT IRON TOWER COMPANY, OF DETROIT, MICHIGAN.

SKELETON TOWER.

SPECIFICATION forming part of Letters Patent No. 297,338, dated April 22, 1884.

Application filed May 31, 1883. Renewed March 17, 1884. (No model.)

To all whom it may concern:

Be it known that I, JOHN S. ADAMS, of Elgin, in the county of Kane and State of Illinois, have invented certain new and useful 5 Improvements in Skeleton Towers; and I do hereby declare that the following is a full, clear, and exact description thereof, reference being had to the accompanying drawings, and to the letters of reference marked thereon, 10 which form a part of this specification.

This invention has reference to towers more particularly intended for the support of electric lamps in cities; and it relates, first, to features of construction by which an equilateral triangular tower may be placed at one corner of a street without obstructing passage beneath it; second, to improvements in tower-elevators for hoisting the attendant to the top of a tower, where he may have access to the 15 lamps; third, to the foundations of a tower; and, fourth, to various matters and details, that will be hereinafter fully specified.

The tower herein shown is of the equilateral triangular prismatic form described in another specification, and more commonly employed at street-intersections in cities. It is to this form of tower that the first part of my 20 invention has more particular reference.

In the drawings, Figure 1 is an elevation of 25 a triangular prismatic tower provided with my several improvements, the base being of the construction adapted to the corner of a street and the foundations of two of the base-uprights being shown in vertical section. Fig. 35 2 is a fragmentary elevation of a similar tower wanting the particular base structure shown in Fig. 1. Fig. 3 is a fragmentary elevation of a similar tower having the single center-post base described in another specification. 40 Fig. 4 is an enlarged view of the base structure shown in Fig. 1, and of superposed parts obtained by a horizontal section at xx of Fig. 1. Fig. 5 is a fragmentary vertical section taken through the indirect line xx of Fig. 4. Fig. 45 6 is a top view of the tower and lamps. Fig. 7 is a fragmentary vertical section taken through xx of Fig. 6. Fig. 8 is a top view of the elevator-cab. Fig. 9 is a vertical section of the cab through xx of Fig. 8. Fig. 10 is an en-

larged view of the lower portion of Fig. 9. 50 Fig. 10^a is a side view of the foot-lever of Fig. 9. Fig. 11 is a detail of the cab-clutch. Fig. 12 is a view partly in section of the devices by which tension is given to the ropes which are used as cab-guides. 55

The special structure for street-corners will be first described, reference being made to Figs. 1, 4, and 5.

A A represent the walks at a street-corner, converging at a right angle, a a indicating the 60 curb-lines, and A' A' the street-crossings. It is desired to erect over the intersection of said walks a skeleton tower which is of equilateral triangular form in horizontal section, and to avoid obstructing either the walks or drive- 65 way by the supporting-posts. To this end a base structure is made, consisting of three uprights, B B' B', the first of which is located at the intersection of the curbs, and the other of which is located at the curbs usually in line 70 with the inner edges of the converging walks, as indicated more plainly in Fig. 4. At a right-angled street-corner said posts will obviously occupy the angles of a right-angled triangle. Ordinarily these posts will be set just outside 75 the curbs, as also indicated in said figure; but they may be otherwise placed, if preferred.

Resting upon the posts B' B' is secured a suitable heavy I-beam, and from the middle point of said beam extends a similar but lighter 80 I-beam, I', the opposite end of which rests upon the post B, as more plainly indicated in Fig. 5. For the proper attachment of said beams to the tops of the posts, I employ recessed castings l², which admit the ends of the 85 beams, and which are preferably united to the tops of the posts B and B' by means of union joints or couplings B², of any suitable construction. A feature of the joints B², as shown, is that they permit a degree of relative inclination, and at the same time afford full bearing of the abutting surfaces, so that the utmost sustaining-power is obtained without the precise accuracy required in plain flange-joints. The beams I and I' form the base or immediate 90 support for the uprights C and C' of the tower proper, the upright C being usually set at a short distance inward from the end of the 95

beam I', as plainly shown in Figs. 4 and 5, and the posts C' C' being set at a greater distance inward from the ends of the beam I, as seen in Fig. 4, so as to form the angles of an 5 equilateral triangle.

As a means of connecting the feet of the uprights C and C' with the I-beams, threaded castings, C², are provided, which have flanges embracing the flanges of said I-beams, as indicated at the right in Fig. 5, so as to hold them laterally in place upon said beam. These castings are suitably tapped to directly admit the correspondingly-threaded ends of the uprights C C', but preferably a union coupling, C³, is interposed. Said coupling will ordinarily be of a construction adapted to afford slight adjustment of the uprights, as indicated in Fig. 5, in order that said uprights may be made exactly vertical, even if the beam be 15 slightly inclined. The construction of the coupling shown is more particularly described in another specification. Any suitable form of ball-and-socket joint will, however, serve the purpose desired.

25 The ends of the I-beams are shown as being secured in the recessed castings I² by means of points d, affixed to the ends of upright tubular posts D, which are threaded downwardly through the tops of the castings I², and which 30 form the corner-posts of a railing, D', that surmounts the posts B B' B'. Suitable recesses, d', are countersunk in the outer surface of the I-beams, to admit said points d, as plainly shown in Fig. 5. D' is an iron grating, which 35 rests upon the I-beams, and also upon transverse rails D³, which bisect the angles formed by said I-beams.

By means of the base structure described, having its uprights B B' located as shown, an 40 unobstructed passage for pedestrians is afforded beneath the tower, and the latter is permitted to stand over the intersection of the walks where it will least obstruct the view in the street, and where it may be more easily 45 guyed or supported from an adjacent building, if desired, in addition to the guys which extend to the curbs from elevated points on the tower. At a suitable height arms E are attached to the uprights C of the tower, to support a railed platform, E', forming a lower landing for the elevator, and at the top of the tower a second railed platform or landing, E², is provided, as shown in Figs. 6 and 7, whence 50 easy access may be had to the lamps F F.

55 The features of improvement relating to the elevator will next be described.

It is intended that the occupant shall raise and lower the cab by his own exertions, and to this end the hoisting-rope is made continuous and is arranged within his reach. The weight of the cab and its occupant is counterbalanced, and the cab is made self-locking, so as to normally remain stationary at any point where it may be arrested.

65 A novel feature of construction in the elevator consists in the combination, with flexible

cab-guides G G, of a clutch or brake attached to the cab, and constructed and arranged to normally hold the cab stationary, being released only by the attendant to allow the necessary movement of the cab. The guides G G are, as described in another specification, suspended from a cross-arm, G', Figs. 6 and 7, which, as here shown, is secured to the central mast, H³, depending from the casting H, 70 joining the converging standards H'. At their lower ends the guides G are joined to a cross-bar, G², similar to the upper bar, G', by which said guide-ropes are held at an equal distance apart. As also stated in another specification, any desired means may be employed to give the necessary tension to the guide-ropes G G; but, as shown in Fig. 12, such tension is given by means of the threaded rod G³, passing centrally downward through the lower 75 cross-bar, G², and entering a coupling, G⁴, supported in place by the rods g g, joined to the tower-uprights C C'. 80

Between the head or nut upon the upper end of the bolt G³ and the cross-bar G² is interposed a stout coiled spring, g', by which the tension of the ropes G G will be maintained, notwithstanding any slight inequality in expansion and contraction that may take place between said ropes and the tower-uprights. Of course said spring g' may be inserted between the coupling G⁴ and the tightening-nut upon the lower end of the rope, if preferred. 90

In Fig. 10 are shown in section the clutching devices by which the cab is held normally stationary on the guide-ropes G. Of these devices J is a central transverse bar, tube, or casting in the base of the elevator J. J² are box shaped castings connected with the base-piece J' by suitable couplings, j, as shown in Fig. 10. Said box-shaped castings J² are open on one side only, and the open sides are directed toward each other. They are, however, additionally provided centrally with vertical apertures, through which the guide-ropes G G may run freely. 100

Within the castings J² are located two recessed-blocks, j' j², which embrace the several guide-ropes G, as plainly seen in Figs. 10 115 and 11.

J³ J⁴ are followers inserted in the open sides of the boxes J², being preferably pivoted to the upper edges of said boxes, as shown at j³, Fig. 10. To these followers are pivotally connected the arms J¹ J⁴, centrally joined to form a toggle-joint, by a downward pressure upon which the followers J³ are forced outward in the boxes J², so as to compress the ropes G between the blocks j' and j². A rod, J⁵, depends 110 from the junction of the toggle-arms J¹, and extends through a recessed casting, J⁶, connected with the rod J', said rod J⁵ having a head or nut on its lower end, and being provided with a spring, j⁴, arranged to draw 115 downward upon said rod, and to thereby depress the toggle and throw out the followers 120

J^3 , so as to grasp the ropes G . Said ropes are released by the foot-lever J' , Figs. 8, 10^a, and 10, by which the toggle and rod J^5 are lifted and the followers J^3 withdrawn from pressure 5 upon the compressing-blocks $j' j^2$.

To the end that the occupant may raise and lower himself with the cab, the latter is connected in the endless rope L , L , trained over the upper and lower pulleys, L' and L^2 , the 10 rope L being arranged to run in proximity to the elevator-cab. The occupant standing at an open side of the cab may thus reach said rope and draw himself upward or downward, as the case may require. For the purpose of 15 rendering this operation comparatively easy, a counter-weight, L^3 , is connected in the rope L , and adjusted, preferably, to accurately counterbalance the weight of the cab and its usual occupant.

20 In operating the elevator the occupant stands with his foot pressed upon the lever J' , so as to hold the clutch-blocks $j' j^2$ free to allow the passage of the guide-ropes G , and when he desires to bring the cab to rest he releases his 25 foot, whereupon the clutch immediately takes effect, and the cab is held stationary. This provision for holding the cab is obviously necessary, particularly to hold the cab at the bottom of the tower, inasmuch as in its absence 30 the counter-weight L^3 will raise the elevator as soon as the weight of the attendant is removed.

A button or hook or any equivalent device applied to lock the elevator-cab by engagement 35 with any stationary part of the tower may be substituted for the rope-clutch described without departure from my invention, albeit the clutch is preferable as being present and operative at all points on the guides.

40 The upper pulley, L' , is arranged, as described in another specification, in one leg, H' , of the tripod at the top of the tower, which is made of the duplex construction shown more plainly in top view of Fig. 6. The lower pulley, L^2 , need not be supported, except by the endless rope L and a depending weight, L^4 , which will serve to keep said rope L taut in place, although a guide or lateral support 45 may be employed, if desired. That part of 50 the hoisting-rope connected with the top of the cab is arranged at one side of the tower-axis in order to allow the top of the cab to rise above the base of the mast H^3 , and to this end the upper cross-bar, J , of the cab, to 55 which said rope is attached, is supported at one side of the axis of the tower or of the cab by means of the brackets $j j$. Arranging the guide-ropes G at one side of a plane through the tower-axis by means of a bent bar, G' , 60 would obviously accomplish the same end.

The next feature of the invention to be described is that relating to the foundations M .

In constructing foundations for towers, and particularly at the intersection of streets in 65 cities, it is desirable that said foundations shall be as limited in breadth as possible,

while at the same time they must be strong enough to contribute materially toward supporting the tower against lateral strain under action of heavy winds.

70

The object of the invention, so far as the same relates to the foundations, is to secure greater unity in the masonry forming said foundations; and to this end it consists in laterally confining or binding the foundation-stones or masonry to the posts beneath the ground-surface.

75

In Fig. 1, M represents the masonry resting upon grout m and upon the bed-plates m' , secured to the lower extremities of the 80 posts B and B' .

M' is a collar surrounding the post beneath the ground-surface and within the masonry, and M^2 are rods running outwardly from said collar in opposite directions, and preferably to 85 all four sides of the masonry M , being provided with the plates m^2 and nuts m^3 at their outer extremities, whereby said masonry is firmly clamped on all sides and held securely in a lateral direction to the post.

90

I claim as my invention—

1. In combination with the post B , set at the angle of the walk, and the posts $B' B'$, set at the opposite side of the cross-walks from the post B , the beam I , joining the posts B' , and 95 the tower-uprights C , C' , and C' , deriving their support from said posts and beams, substantially as described.

2. In combination with the tower-uprights C , C' , and C' , the base structure described for 100 the intersection of street-walks, consisting, essentially, of the posts B , B' , and B' , set in the relative position shown, and the beams I and I' , joining said posts, and forming the immediate supports for the tower-uprights, substantially as described.

3. In combination with the posts B and B' , and with the connected beams I and I' , arranged as shown, the recessed castings I^2 , 105 mounting the posts, and means for securing the ends of the beams to the said castings, substantially as described.

4. In combination with the posts B and B' , and with the beams I and I' , the castings I^2 , forming seats for the ends of the beams, and 115 adjustable union-joints B^2 , connecting said castings with the posts, substantially as described.

5. In the base tower structure described, the combination, with the beams I and I' and 120 recessed castings I^2 , of the points d , inserted through the castings I^2 , and entering the beams, substantially as described.

6. In combination with the recessed casting I^2 and beam I or I' , the rail-post D , threaded 125 through the upper surface of said casting I^2 , and the point d , set in the lower end of the post D , substantially as described, and for the purposes set forth.

7. In a tower, the combination, with the 130 elevator-cab and its guides, of an endless hoisting-rope, having the cab connected therein,

and a counter-weight connected in said rope, said rope being arranged in convenient reach of the occupant of the cab, substantially as described, and for the purposes set forth,

5 8. In combination with the elevator-cab, the hoisting-rope arranged in convenient reach of the occupant, a counter-weight connected with the rope, and means for holding the cab stationary in the absence of the occupant, substantially as described.

9. In combination with the cab-hoisting rope, counter-balance, and means whereby the occupant may raise and lower the cab, means for normally holding the cab locked to the 15 guides, and means whereby the occupant may release the cab, substantially as described.

10. In combination with the cab, and with the flexible guide-ropes G therefor, the boxes

J², suitable clutch-blocks contained therein, followers J³, toggle-arms J⁴, means for normally depressing the toggle, and means whereby the occupant may release the toggle, substantially as described.

11. In combination with the base posts or post of a tower, and with the masonry forming the foundations of the same, the collar M' and rods M², provided with suitable nuts external to the masonry, substantially as and for the purpose set forth.

In testimony that I claim the foregoing as 30 my invention I affix my signature in presence of two witnesses.

JOHN S. ADAMS.
